UNITED STATES PATENT OFFICE.

HENRY A. WISE WOOD, OF NEW YORK, AND JOHN A. ISBELL, OF MIDDLETOWN, NEW YORK, ASSIGNORS, BY MESNE ASSIGNMENTS, TO WOOD NEWSPAPER MACHINERY CORPORATION, OF NEW YORK, N. Y., A CORPORATION OF VIRGINIA.

PAPER-ROLL-SUPPORTING MECHANISM.

1,242,506.

Specification of Letters Patent. Patented Oct. 9, 1917.

Application filed June 5, 1913. Serial No. 771,856.

To all whom it may concern:

Be it known that we, HENRY A. WISE and JOHN A. ISBELL, citizens of the United States, said Wood residing at New York, county and State of New York, and said ISBELL residing at Middletown, in the county of Orange and State of New York, have invented a new and useful Paper-Roll-Supporting Mechanism, of which the following is a specification.

This invention relates to the spindle for carrying a paper roll for use on a web printing press. Heretofore so far as we are aware, bearings have been fixed on the brackets which support the web rolls and spindles and they have been arranged to be removed from the bearings.

The principal object of this invention is to provide a construction in which the spindle will not have to be removed from the bearings when taken from the machine, so that the bearings shall always properly fit the spindle and so that the placing of the paper roll in position may be facilitated. A further object of the invention is to provide improvements in the adjustment of the cones for fastening the paper rolls to the spindle. The invention also involves improvements in details of construction and combinations of parts as will appear hereinafter.

Reference is to be had to the accompanying drawings in which—

Figure 1 is a side view of the end of a web printing press showing several rolls supported thereon, and also illustrating two of the roll spindles in transverse section;

Fig. 2 is a detail elevation of a paper roll mounted on its spindle on an enlarged scale showing the brake pulley in central section;

Fig. 3 is a similar view of a portion of the spindle on a further enlarged scale showing the connected parts in section along a central longitudinal plane;

Fig. 4 is an end elevation of one of the cones;

Fig. 5 is a side view on enlarged scale of a portion of the supporting brackets and locking device; and

Fig. 6 is an enlarged sectional view of the bracket on the line 6—6 of Fig. 1.

Fig. 1 shows three web rolls A in their final positions on the machine, and shows

in dotted lines the initial positions of two of these rolls when first placed on the brackets 10 which are carried by the frame 11 of the web press. The bottom bracket 10^a is constructed differently as is well understood in this art to receive a roll directly from the floor. The upper brackets, however, are each provided with a substantially horizontal surface 12 having a projection 13 at its outer end and a depression 14 at its inner end. By means of a series of studs 15 a track or guide 16 is mounted at a distance 65 from the side of each of these upper brackets. It terminates in an inclined surface 17 adjacent to the depression 14. Above this depression 14 is a cap or clamp 18 pivoted at 19 and provided with a spring-pressed 70 latch 20 adapted to engage a pin 21 on the bracket.

The paper roll carrying spindle 25 is shown as provided with a key-way 26. In this fit loosely keys 27 each mounted on an inner ball-race support 28. Each of these carries the inner member 29 of a ball-race and is provided with screw-threads on the end for receiving a pair of nuts 30 and 31 for fixing the ball-race in position. An outer housing 32 is provided having a seat for the outer member of the ball race and a seal 33 is arranged as usual in the open end of this housing and fixed thereto. This housing is of a substantially cylindrical 85 form outside, but has flanges 34 at its edges. This housing constitutes a roll adapted to fit on the surface 12 and in the depression 14 and to be engaged and held by the cap 18 when the latter is in locked position as 90 shown in Fig. 1.

On one end of the spindle 25 is located a brake drum 35. This is provided with a circumferential groove 36 at a proper distance from the adjacent housing 32 to engage the track 16 when the housing of the bearing is rolling along the surface 12. The outer end of this track is depressed as shown in Fig. 1. It will be obvious that when the roll is placed on the two brackets in the dotted line position the engagement of the track in the groove 36 will guide the roll properly into the depression 14. Then the cap can be brought down into fastening position. This affords a convenient and quick means for placing the paper rolls in position and pro-

vides an easy running support for them. Moreover, as these bearings are removable with the web roll spindle, they are always properly located thereon.

5 It is to be understood that the key 27 of each of the bearings fits loosely in the key-way 26 so that the spindle can be moved longitudinally for the purpose of properly registering the paper roll. In spite of this 10 fact, however, the spindle is properly guided into place on the brackets by the brake pulley itself as has been stated already. The side register can be made by means of a movable disk 56 adapted to enter the groove 15 36 when the spindle is in proper position in the press. The track 16 guides the drum into proper position to cause the disk to enter the groove.

For the purpose of holding the paper roll 20 and securing it properly in position the following mechanism is provided. A split cone 40 is arranged with a key 41 passing loosely into the key-way 26 and a bolt 42 is provided for clamping this cone in position on 25 the spindle. Ordinarily this cone is secured in one position and is not adjusted thereafter so it may be considered as a fixed cone. The key 41 projects beyond the conical surface of the cone.

30 Near the other end of the spindle and facing the cone 40 is an adjustable cone 44. This cone is provided with a circumferential shoulder 45 at the back. Over it is mounted a sleeve 46 having a projection extending down over the shoulder and free to turn. Fixed to the inside of this sleeve is a nut 47. A collar 48 back of this nut is provided with a screw-threaded projection entering the nut. This collar is split and provided with a bolt 49 for clamping it in position on the spindle. In practice this collar is moved to a convenient position on the spindle taking the movable cone 44 with it. Then the collar is fastened to the spindle. 40 45 The sleeve 46 can then be turned to adjust the cone 44 to proper position along the spindle. This cone 44 is provided with a key 50 which projects into the key way loosely and prevents the rotation of the cone. It also projects beyond the conical surface of the cone.

50 The paper spindle itself is provided with a hollow core 51 having a sheet of metal 12 at each end surrounding its outer surfaces 55 and shaped on the interior to fit the two cones. At each end it is provided with a slot 53 for receiving the keys 41 and 50. In this way a quickly-adjustable arrangement is provided for fastening the paper roll to 60 the spindle and yet one which can be adjusted as a whole longitudinally of the spindle when required.

Although we have illustrated and described a single specific embodiment of the 65 invention, we are aware of the fact that

many modifications can be made therein by any person skilled in the art without departing from the scope of the invention as expressed in the claims. Therefore we do not wish to be limited to the details of construction herein shown and described, but what we do claim is: —

1. In a roll supply mechanism, the combination of a pair of roll supporting surfaces having depressions therein, with a roll 75 carrying spindle having a relatively rotatable housing thereon adapted to seat in said depression, bearings between the housing and spindle, and means for holding said housing in said depression.

2. The combination with a bracket having a substantially horizontal surface provided with a depression at the inner end thereof, of a paper roll-carrying spindle having a ball-bearing mounted thereon for engagement with said horizontal surface and adapted to enter said depression, and a clamp on said bracket adapted to engage the outside of said bearing when in said depression and hold it in position therein.

3. The combination with a bracket having a substantially horizontal surface, of a paper roll carrying spindle having a ball bearing mounted thereon for engagement with said horizontal surface, whereby the 95 spindle can be supported from said horizontal surface by the bearing, and a clamp adapted to engage the outside of said bearing to hold it in stationary position on said surface.

4. In a roll carrying mechanism, the combination of a roll supporting surface, with a roll carrying spindle having a relatively rotatable housing thereon adapted to roll along said surface, bearings between the 105 housing and the spindle, and means for holding the housing on said surface.

5. The combination with a supporting bracket having a roll supporting surface, of a paper roll carrying spindle having a roll 110 thereon adapted to roll along said surface, a brake pulley on said spindle provided with a circumferential groove, and means for engaging in said groove to move the spindle longitudinally in said roll, whereby the 115 spindle will be supported by the roll on said surface in all its adjusted positions.

6. The combination with a supporting bracket having a guide track thereon and a roll supporting surface, of a paper roll 120 carrying spindle having a brake pulley thereon provided with a circumferential groove for engagement with said track for guiding the spindle longitudinally while the roll moves along said surface.

7. The combination with a supporting bracket having a guide track thereon and a roll supporting surface, of a paper roll-carrying spindle having a brake pulley thereon provided with a circumferential 130

groove for engagement with said track, and means for engaging in said groove to move the spindle longitudinally.

8. The combination with a supporting bracket having a guide track thereon and a roll supporting surface, of a paper roll-carrying spindle having a brake pulley thereon provided with a circumferential groove for engagement with said track, and an annular roller bearing on said spindle for engagement with said surface.

9. The combination with a bracket having a substantially horizontal surface provided with a depression at the inner end thereof, of a guide track supported by said bracket at a distance from the face thereof and terminating beyond said depression, a paper roll-carrying spindle having a ball-bearing mounted thereon for engagement with said horizontal surface and adapted to enter said depression, and a brake pulley also on said spindle having a groove for registration with said track, whereby the spindle will be guided into proper position by the track.

25 10. The combination with a bracket having a substantially horizontal surface provided with a depression at the inner end thereof, of a guide track supported by said bracket at a distance from the face thereof, and a paper roll-carrying spindle having a ball-bearing mounted thereon for engagement with said horizontal surface and adapted to enter said depression, a brake

pulley on said spindle having a groove for registration with said track, and a clamp on 35 said bracket adapted to engage the outside of said bearing when in said depression and hold it in position therein.

11. The combination with a paper roll carrying spindle, of a fixed cone thereon, a 40 second cone slidably mounted on the spindle, a sleeve connected with the second cone, a nut secured inside said sleeve, and a collar having a screw-threaded projection entering said nut and adapted to be clamped to 45 the spindle.

12. The combination with a paper roll carrying spindle, of a cone for engaging the paper roll, loosely keyed to the spindle and slideable therealong, said cone having a circumferential shoulder at the end thereof, a sleeve extending over said shoulder and free to turn thereon and having a nut fixed to the inside thereof, and a collar beyond the nut provided with a screw-threaded projection entering the nut, said collar being adapted to be clamped to the spindle.

In testimony whereof we have hereunto set our hands, in the presence of two subscribing witnesses.

HENRY A. WISE WOOD.
JOHN A. ISBELL.
